UNITED STATES PATENT OFFICE

EUGENE ALLEN PARKER AND ROY CUTSINGER, OF MORRILTON, ARKANSAS

NONSINKABLE BOAT

Application filed March 23, 1931. Serial No. 524,714.

This invention appertains to new and useful improvements in boats and more particularly to a boat of the non-sinkable type, particularly adapted for use in fishing and 5 hunting.

An important object of the invention is to provide a non-sinkable skid providing a combination for caught fish and game, and also affording convenience and safety in use.

10 Other important objects and advantages of the invention will become apparent to the reader of the following specification.

In the drawings:—

Figure 1 represents a top plan view of the 15 boat in its entirety.

Fig. 2 represents a side elevational view of the boat in its entirety.

Fig. 3 represents a top plan view of the 20 boat with the cover board removed, along with the game compartment closures, and further showing the tops of the air compartments broken away.

Fig. 4 represents a longitudinal sectional view taken substantially on the line 4—4 of 25 Fig. 3.

Fig. 5 represents a side elevational view of the cover board and flooring support.

Fig. 6 represents a transverse sectional view through the boat.

30 Fig. 7 represents an enlarged fragmentary detailed sectional view through one of the game compartments.

Referring to the drawings wherein like numerals designate like parts, it can be seen 35 that the boat construction includes the bottom 5 upon which forward and rearward groups of air chambers are formed by the transversely and longitudinally extending partitions 6 and 7 respectively. The forward compartments are covered by the plate 8, while the rearward compartments are covered by the plate 9, and is apparent in Fig. 2, the side walls 10 extend entirely around the boat, and is so constructed as to 40 provide auxiliary air chambers 11 and at opposite sides of the rearward air compartments.

Additional air compartments 12—12 are provided adjacent the intermediate portions 50 of the boat and between these compartments

12—12 and the compartments 11—11 are the containers 13 having openings 14 in the bottom thereof.

Above one of these containers 13 is the frame 15 for hingedly supporting the closure 55 16 which is provided with a handle 17. The other container 13 has a frame 18 arranged above the same, for supporting the hinge pin 19 which swingably supports the pair of closures 20—20.

It will be observed, that the plate 8 as well as the bottom 5 of the boat construction tapers forwardly so that the front end of the boat is pointed.

Referring now to Figs. 6 and 7, it can be 60 seen that mesh baskets 21 can be disposed into the compartments 13 and furthermore, suitable fastening means 22 can be provided on the closures 20 and 16.

Disposed over the forward air compartments and extending rearwardly over the rearward air compartments, is the top cover board 23 provided with the substantially ovate-shaped opening 24 at the intermediate portion thereof. This board 23 is secured to 70 the plates 8 and 9 by bolts 25.

Depending from the board 23 into the compartments 25 between the forward and rearward air compartments, are the U-shaped 75 saddles 26—26 for supporting the slats 27 80 making up a flooring for supporting the occupants.

Obviously, the occupants can sit upon the board 23 with their feet resting upon the slats 27, and a substantial number of the compartments of the forward and rearward groups must be punctured before the boat 85 will tend to sink.

While the foregoing specification sets forth the invention in specific terms, it is to be understood that numerous changes in the shape, size and materials may be resorted to without departing from the spirit and scope of the invention as claimed hereinafter.

Having thus described our invention, what 90 we claim as new is:—

1. A boat of the character described comprising a bottom, a top, a side wall, an occupant compartment, air compartments forwardly and rearwardly of the occupant com- 100

partment, and a pair of air compartments at each side of the boat and a utility receptacle between the pair of air compartments at each side of the boat.

- 5 2. A boat of the character described comprising a bottom, a top, a side wall, an occupant compartment, air compartments forwardly and rearwardly of the occupant compartment, a pair of air compartments at each 10 side of the boat and a utility receptacle between the pair of air compartments at each side of the boat, and the bottoms of the said receptacles being perforated and mesh baskets for disposition within the said receptacles.
- 15 3. A boat of the character described comprising a plurality of air compartments arranged in forwardly and rearwardly spaced relation to provide an occupant compartment, a cover board for the tops of the compartments and provided with an opening registering with the occupant compartment, and a platform depending from the cover board into the said occupant compartment.
- 20 4. A boat of the character described comprising forward and rearward air compartments arranged in spaced relation to provide an occupant's compartment, a cover board for disposition over the air compartments, said cover board being provided with an opening 25 therein registering with the occupant compartment, hangers depending from the said cover board into the occupant compartment, and a platform in the occupant compartment supported by the said hangers.

In testimony whereof we affix our signatures.

EUGENE ALLEN PARKER.
ROY CUTSINGER.
